IDENTIFICATION CLIP FOR KEYS

Campbell Carrington, New York, N. Y.

Application October 26, 1937, Serial No. 171,117

2 Claims. (CL 40—23)

This invention relates to identification clips.

More specifically the invention relates to clips for detachable connection with keys whereby any desired key may be readily selected from a number of keys whether in the light or dark when such selection is made.

It is a well recognized fact that much difficulty is often experienced in readily selecting any desired key from a number of keys whether the 10 keys be similar in appearance or of marked dissimilarity.

Many persons carry a great number of keys which may be on rings or otherwise bunched, and while such persons may have had considerable 15 experience in the use of the various keys in their possession, they are in most cases unable to immediately select any desired key from the group of keys, due particularly to the fact that the keys now in use, and particularly in buildings, are 20 substantially uniform in appearance.

Furthermore, it is a fact that the majority of persons who carry only a few keys have difficulty in selecting any desired key. Thus, e. g., the automobile ignition key and spare tire keys are quite 25 dissimilar in appearance and the possessor of such keys may have learned to readily distinguish such keys, and yet he at times forgets which is which and is accordingly obliged to spend some time in ascertaining the correct key.

30 While it is in many instances difficult to select any desired key from a group thereof by the aid of light, it is almost impossible to select same in the dark, even when the keys are substantially different in size and appearance.

35 A primary object of the invention is the provision of key identification clips which may be readily engaged with the heads of keys, and which bear designs or characters discernible by the senses of both sight and touch.

40 A further object of the invention is the provision of key identification clips, each comprising a head provided with a design or character and a substantially U-shaped yieldable key engaging member secured to the head, whereby the clip is 45 capable of being frictionally engaged with the head of a key by pushing same edgewise of the head until such yieldable member springs over and frictionally engages the head.

45 A still further object of the invention is the 50 provision of key identification clips which are capable of rapid and inexpensive construction by stamping same from strips of sheet steel.

55 A still further object of the invention is the provision of key identification clips which are simple in construction, easy to apply to keys, posi-

tive in retaining their fixed position on the keys, highly efficient in identifying the various keys, and which can be manufactured at very low cost.

In the accompanying drawing:

Figure 1 is a perspective view of a key having 5 one form of the invention engaged therewith.

Figure 2 is a plan view of a key having a clip 10 of different form engaged therewith.

Figure 3 is a top plan view of a clip constructed 15 in accordance with one embodiment of my invention.

Figure 4 is an edge view of the clip illustrated in Figures 3 and 4.

Figure 5 is a bottom plan view of the clip illustrated in Figures 3 and 4. 15

Figures 6, 7 and 8 are top plan views of clips, each disclosing a different form of design or character for identifying a key to which it may be secured.

Figures 9 and 10 are edge views of clips, each 20 disclosing a modified form of key engaging members.

Figure 11 is a plan view of a stamped blank for providing a dual clip.

Figure 12 is an edge view of a finished clip 25 formed from the blank shown in Figure 11.

Referring to the drawing C designates a clip which is formed with a head 10 and a yieldable key engaging U-shaped member 11. The head 10 is disclosed as of circular or disk form, but 30 may be of any other desired form, and the thickness of the relatively thin head may be varied as well as the outer surface contour, which in the drawing is shown as of slightly convex form.

The head 10 may be constructed of any desired 35 material, but preferably of such material that the leg of the spring steel key engaging member 11 can be soldered or otherwise secured thereto.

The yieldable member 11 is preferably constructed from a relatively narrow strip of spring steel and has one leg 12 secured by soldering to the bottom face of the head 10, and the other leg 13 normally converging toward the head 10 for a purpose later described. 40

Suitably secured to or integral with the head 10 is a design or character 14, which in Figures 2 to 5, inclusive, is shown as a star, and which as clearly indicated in Figure 4 is raised above the upper surface of the head 10. 45

A clip as thus described and constructed is readily engageable with the head of a key K by pushing the clip edgewise of the key head and entering said head of the key between the legs 12 and 13, the converging leg 13 yielding away from 50 55

the other leg 12 and with the key head frictionally engaged between the legs, whereby the clip is maintained on the key without accidental disengagement thereof.

- 5 By providing the star or any other character or design of raised form it will be readily distinguished by the sense of touch in the dark. Various other forms of characters may be used. Thus in Figures 1 and 6 are illustrated raised concentric circles, and in Figure 7 is illustrated a raised triangular figure, while in Figure 8 is illustrated a head having the word "Office" thereon, the letters of which may be raised for identification by the sense of touch.
- 10 In Figures 1 and 9 are illustrated a clip having a key engaging member 15, the bend in which is disposed outwardly of the head 10, whereby the head 10 may be positioned nearer the center of the key head, as shown in Figure 1.
- 15 In Figure 10 is shown a still further form of key head engaging member 16, the bend in which is downwardly offset and the lower leg is substantially normally parallel with the upper leg. In this form the offset bend allows for expansion 20 of the member 15 in engaging the key head, and the lower leg will engage the key head throughout its length thereby providing a greater frictional grip. The heads 10 of the clips may be provided with various forms of designs and characters whereby each key of a group thereof may 25 be provided with a clip having different marks, thus providing identification marks for the keys.

Sometimes only one or two keys of a bunch of keys are used frequently in which event these 30 keys could readily be selected if they were provided with a clip such as described herein. The clip heads 10 may be provided with designs or characters only or with words only, such as "House" and "Office" or both may be used if 35 desired. The clips may embody two heads 10, one secured to each leg of member 11, and one

provided with a raised design for identification in the dark, and the other having a word for quick identification in the light.

In Figures 11 and 12 is illustrated a key identification clip C' which embodies a pair of oppositely positioned heads 10' and a yieldable connecting member 11' integral with the heads 10'. This form of clip is capable of economical manufacture as it can be readily formed from a flat blank B as illustrated in Figure 11, and the blanks 10 can be expeditiously and economically stamped from sheets of sheet steel.

The heads 10' are provided with suitable characters or designs such as a house, etc., and which is preferably applied prior to bending of the 15 blanks into finished clip form. The characters or designs may be embossed on the heads 10' in order that the same may be readily distinguished by the sense of touch.

The clips C' are formed merely by bending the 20 blanks centrally thereof and intermediate the heads 10', thereby providing clips each having a head for disposition on each side of the key head.

What is claimed is:

1. The combination with a key head having an 25 arcuate edge, of an identification clip for attachment thereto comprising a narrow resilient strip of uniform width bent into U-form and having relatively large heads on the legs thereof, said heads being identical in shape and having their 30 marginal edges in the same plane, said strip operating to hold the entire area of the opposed faces of the heads yieldably engaged with the opposite faces of the key head when the legs of the strip straddle the key head, the bight of the 35 strip engaging and throughout its width contacting with said arcuate edge.

2. The structure as defined in claim 1, wherein the heads have thereon means for identifying a 40 particular key.

CAMPBELL CARRINGTON.
